UNITED STATES PATENT OFFICE.

FRANK H. MITCHELL, OF NEW YORK, N. Y., ASSIGNOR OF ONE-THIRD TO CHARLES T. ROOT, OF EAST ORANGE, AND CHARLES G. PHILLIPS, OF MONTCLAIR, NEW JERSEY.

DRESS-SHIELD ATTACHMENT.

SPECIFICATION forming part of Letters Patent No. 603,773, dated May 10, 1898.

Application filed July 15, 1897. Serial No. 644,601. (No model.)

To all whom it may concern:

Be it known that I, FRANK H. MITCHELL, of the city and county of New York, in the State of New York, have invented a new and 5 useful Improvement in Dress-Shield Attachments, of which the following is a specification.

This invention relates to what are commonly known as "dress-shields" and attached 10 to those portions of dresses which come under the armpits.

The object of the improvement is to provide means for attaching the shield to the dress which permits of its being easily detached for 15 washing or any other purpose and as easily replaced.

A device embodying my invention consists of two clasping members of metal, one of which is to be removably applied over the 20 seam between the waist and the sleeve of the dress, and the other of which is permanently attached to the shield within the fold thereof and serves both the purpose of securing the first-mentioned member to the dress and 25 the purpose of securing the shield in place therein.

I will first describe my improved attachment with reference to the accompanying drawings and afterward point out its novelty 30 in a claim.

Figure 1 is a side view of that portion of a dress which comes under the armpit and of a shield applied thereto with my attachment. Figs. 2 and 3 represent, respectively, on a 35 larger scale than the real size, a side view and an edge view of that member of my device which is attached to the dress. Figs. 4 and 5 represent, respectively, an edge view and a side view of that member which is permanently attached to the shield. Fig. 6 represents a transverse sectional view of the fold of the shield, the portions of the dress which come under the armpit, and an end view of my attachment. Fig. 7 shows a hook which 40 may be used as an adjunct to my attachment. Fig. 8 is a side view representing a modification of my attachment.

Similar letters of reference designate corresponding parts in all the figures.

50 The member A, which is to be removably

attached to the dress, consists of two small metal jaws hinged or flexibly connected at their upper edges, as shown at a, and having their lower edges turned toward each other and serrated, as shown at b b. The other 55 member B, which is to be permanently attached to the shield C, consists of a metal clip or clasp made in the form of a loop or bow and having its lower edges turned toward each other to form rounded inward projections, as 60 shown at c in Fig. 5. This member should have such stiffness and elasticity that its lower edges c may be sprung apart to enable the clasp to be passed over the member A, and that when so passed over it may clamp 65 the two jaws of the said member A. The width of the jaws of this member B should preferably be somewhat less than that of the jaws of the member A, as may be understood by a comparison of Figs. 2 and 4. The jaws 70 of the member A are formed with external indentations d, which run lengthwise thereof to receive the rounded turned-in edges c of the member B, for the purpose of holding down the fold of the shield snugly to the 75 armhole-seam. At the ends of these indentations outward projections e are formed for the purpose of preventing the accidental longitudinal displacement of the two members A and B relatively to each other. 80

The above description applies to the example of the invention illustrated by Fig. 8 as well as to that illustrated by the other figures. The only difference between the two examples is that shown in Fig. 8. The two 85 members are permanently connected together, as indicated at f, and in the other example there is no such connection, but they may be entirely separated when the shield is not applied to the dress D. Two of these 90 attachments or attaching devices will be sufficient for each shield, applied one near each end of the latter, as shown in Fig. 1.

The members B when placed within the fold of the shield, as shown in Figs. 1 and 6, 95 may be permanently connected therewith in any suitable manner, as by sewing, with thread passing through the head g of the clasps or members B and through the shield, as indicated at h.

To apply the shield to the dress, the two members A with their jaws open, as shown in Fig. 3, are placed at a proper distance apart over the edge of the armhole *i*. The members B, which have been before mentioned as permanently secured to the shield, are then placed over the members A so far that the rounded lower edges *c* of the former enter the indentations *d* of the latter and force the lower 5 serrated or toothed edges *b* of the member A into the fabric of the dress, as shown in Fig. 10, and the shield is thus retained in place within the armhole of the dress.

It has been hereinbefore mentioned that 15 the members B of the attachment are permanently attached to the shield, yet one pair of these attachments may serve for many shields, as when one shield is worn out the members B of the attachment may be cut 20 off or detached and be attached to a new shield.

In order to confine the lower edge of that loop of the shield which comes within the

body of the dress, I prefer generally to use in connection with my attachment a hooked pin 25 E, such as is shown in Fig. 7 and also shown in Fig. 1, the shank *j* of the said pin being sewed to the shield and the pin serving to hook into the waist-lining of the dress.

What I claim as my invention is—

An attachment for dress-shields consisting of two separable members one comprising two flexibly-connected jaws in the exteriors of which are indentations and the other comprising a spring-clasp having its ends turned 30 inwardly to enter the said indentations, the said jaws being further provided with external projections at the ends of the indentations for preventing the accidental longitudinal displacement of the two members relatively to each other, substantially as set forth. 35

FRANK H. MITCHELL.
